APPARATUS FOR CASTING JOINTED
MEMBERS

George C. Clark, Beverly Hills, Calif.

Application February 8, 1934, Serial No. 710,280

11 Claims. (Cl. 22—126)

The invention relates to apparatus for casting jointed members, and particularly for casting the toe and heel portions of an articulated hollow metal shoe last.

5 The primary object of the invention is to provide means for casting the sections of a jointed member with finished joint faces whereby the expensive operation of machining such faces is eliminated and assurance can be had that the joint members of the articles to be cast will properly cooperate and interfit to provide the jointed article with the required shape, contour and interfitting relation.

10 A further object is to provide means for casting sections of a jointed member with integrally formed joint-forming members.

15 A further object is to provide means for casting a member with a pocket formed therein and open at a face thereof.

20 A further object is to provide means for casting a member having a projecting portion in which a preformed member is imbedded.

25 A further object is to provide means for casting a member with a portion having a preformed member imbedded therein and with a bore for the reception of another member, said preformed member and last named member to sustain the wear to which the member to be cast is subjected.

30 A further object is to provide means for casting a member having a preformed tubular member imbedded therein with means for supporting said preformed member and preventing molten metal from entering therein.

35 A further object is to provide a casting flask with a chill forming at least one face of a mold impression and a second chill operatively supported by said first chill and projecting from said flask.

40 A further object is to provide a casting flask with a chill forming at least one face of a mold impression and a second chill shiftably carried and operatively positioned by said first chill.

45 With the above and other objects in view, the invention resides in the combination and arrangement of parts as hereinafter set forth, shown in the drawings, described and claimed, it being understood that changes in the precise embodiment of the invention may be made within the scope of what is claimed without departing from the spirit of the invention.

50 In the drawings:

Figure 1 is a view in side elevation of the shoe last to be cast.

55 Figure 2 is a longitudinal vertical sectional view of the shoe last.

Figure 3 is a fragmentary perspective view of the toe member of the last.

Figure 4 is a fragmentary perspective view of the heel member of the last.

5 Figure 5 is a fragmentary top plan view of the drag and core supporting means of the casting apparatus for casting the toe member of the last.

10 Figure 6 is a fragmentary longitudinal vertical sectional view of the toe member casting apparatus taken on line 6—6 of Figure 5.

15 Figure 7 is a transverse vertical sectional view of the toe member casting apparatus taken on line 7—7 of Figure 5.

Figure 8 is a fragmentary top plan view of the drag and core supporting means of the apparatus for casting the heel member of the last.

20 Figure 9 is a fragmentary longitudinal vertical sectional view of the heel member casting apparatus taken on line 9—9 of Figure 8.

25 Figure 10 is a transverse vertical sectional view of the heel member casting apparatus taken on line 10—10 of Figure 8.

Figure 11 is a perspective view of one part of a chill carried by the toe member casting apparatus.

30 Figure 12 is a perspective view of a pin employed in the toe member casting apparatus.

Figure 13 is a perspective view of one part of a chill carried by the heel member casting apparatus.

35 Figure 14 is a perspective view of another part of the chill carried by the heel member casting apparatus.

40 Referring to the drawings, which illustrate one embodiment of the invention, and particularly to Figures 1 to 4, the numeral 20 designates a hollow aluminum shoe last comprised of a toe member 21 and a heel member 22, which are pivotally interconnected. The joint face 23 of toe member 21 has a semi-cylindrical knuckle 24 projecting therefrom intermediate the sides thereof and adjacent the lower face thereof, the axis of said knuckle extending transversely of said joint face. On opposite sides of said knuckle, and concentric therewith are provided recesses 25. The joint face 26 of the heel member 22 has a pair of spaced, aligned semi-cylindrical knuckles 27 projecting therefrom at opposite sides thereof to fit into the recesses 25 of the toe member. A recess 28 concentric with and between knuckles 27 is formed in joint face 26 to receive knuckle 24 of toe member 21.

45 Knuckles 27 have aligned central apertures 29 formed therein, and knuckle 24 has a hard metal sleeve 30 centrally imbedded therein, and the apertures 29 receive a joint pin 31 which is journaled in said sleeve 30.

5 Integrally formed with heel member 22 is a pocket member 32 whose mouth opens at the recess 28. This pocket mounts a coil spring 33 which urges a hard metal ball 34 against knuckle 24 of the toe member. A radial bore or opening 35, whose axis extends at an angle to the axis of pocket 32 when the last parts are positioned as 10 illustrated in Figure 1, is formed in the knuckle 24 of the toe member, and in this bore 35 is fixedly disposed a hard metal ball 36 which partially projects from the knuckle 24.

15 The last members are relatively pivotal about pin 31, said pin being carried by knuckles 27 and journaled in sleeve 30. In the pivoting of the last members, the spring pressed ball 34 rolls over the portion of ball 36 projecting from knuckle 24, and the last members are thus thrown to and locked at one or the other of their extremes of 20 pivotal movement.

20 The casting apparatus forming the subject matter of this application is intended particularly for the casting of a jointed shoe last of the character above described, and is illustrated in Figures 5 to 14. The apparatus utilizes a flask comprising a drag 40 and a cope 41, each of which is filled with formable material 42, such as sand, which is firmly packed therein. A longitudinal shoulder 43 is carried by and projects outwardly of the face of each of the longitudinal sides of the 25 drag, and these shoulders support a frame 44 which is spaced from the sides of the drag for the major portion of its extent, but which carries a plurality of inwardly directed portions 45 which engage the drag to position frame 44 in the exact 30 required relation to the drag. A clamp 46 is carried by the frame 44 to support an arbor 47 on which a core 48 is mounted, said arbor passing through suitable registering recesses in the drag and cope. Core 48 is disposed in a mold impression 49 formed in formable material 42 of the 35 drag and cope.

40 The drag and cope each mount, imbedded in the sand thereof, and operatively held by said sand, one part of a two-part chill 50, and the mold impression is formed in said drag and cope to expose at least a portion of said chill, the latter thus forming at least one face of said mold impression. These chills, as well as cores 48, are 45 differently constructed for use in the casting of the toe member, than for use in the casting of the heel member. Figures 5, 6, 7, 11 and 12 illustrate the particular construction of the toe member flask, chill and core; and Figures 8, 9, 50 10, 13 and 14 illustrate the particular construction 55 of the heel member flask, chill and core.

55 The chill member 51, illustrated in Figure 11, and employed in casting the toe member of the last, is carried by the drag and comprises a vertical plate 52 and a horizontal plate 53. Substantially centrally in horizontal plate 53 is formed a transverse recess 54 of semi-circular cross sectional outline for the reception of the core arbor 47, as illustrated in Figure 5. In spaced relation to recess 54, a vertical recess 55 of semi-circular cross sectional outline is formed in plate 52. A cylindrical plug 56 is mounted in recess 55 and extends for the major portion of the length thereof to terminate in spaced relation to the face of plate 53, one half of said plug 60 projecting outwardly of the face of plate 52. In plate 53 is formed a recess 57 of semi-circular outline which extends radially of plug 56 and in spaced angular relation to recess 54, said recess being adapted to receive the pin 58, illustrated in 65 70 Figure 12, for purposes to be hereinafter set forth.

75 The chill parts 51 carried by the drag and cope are of complementary construction, and the drag carried part thereof carries a pin 59, as illustrated in Figure 11, projecting longitudinally and centrally from plug 56 for a distance approximately twice the dimension of the spacing of the adjacent horizontal faces of plug 56 and plate 53.

80 In the casting of the toe member of the last, the preformed hard metal sleeve 30 is inserted over pin 59 of the drag-carried chill 51; pin 58 is disposed in chill recess 57 in a position to project partially into recess 55 at one end, and the core 48 is positioned in the portion of impression 49 formed in the drag, the arbor 47 mounting said core being supported and positioned by frame 44 and by recess 54 of the chill 51. The cope 41 is 85 then positioned on the drag in registering relation thereto, with the plates 53 of chills 51 disposed in face contacting engagement, and the aluminum or other metal of which the last is to 90 be formed is then poured into the mold impression. The metal flows into and fills the mold impression 49 and also the recess 55 of chill 51. After the metal has set, but preferably before it has cooled, the cope is removed to permit withdrawal of pin 58 which forms opening or bore 35 in the knuckle 24, which knuckle is cast in the recess 55 of chill 51. When the metal has cooled the molded last member may be removed from the drag by vertical movement to release the 95 knuckle 24 and its imbedded sleeve 30 from pin 59. The last member is thus cast against a chill which forms, in the casting operation, the joint face thereof, including the knuckle 24 and recesses 25, and the ball receiving bore 35, and also 100 imbeds the sleeve 30 in the knuckle. Thus the only operation necessary to commercially complete the member is to finish the faces thereof, except the joint face, the finishing of which joint face in the casting operation simplifies the operation of the machine finishing by giving a start from which to work and with reference to which the machine finishing can be accurately done.

105 The chill member 60, illustrated in Figure 13, and employed in molding the heel member of the last, comprises a horizontal plate 61 and vertical plates 62 and 63 which are relatively angularly disposed. A vertical recess 64 of arcuate cross sectional shape is formed in faces 62 and 63, and the center of said recess is coincident with the intersection of projections of the faces of said plates 62 and 63. In the plate 61 is formed a transverse recess 65 of rectangular cross sectional shape, the width of said recess 65 being substantially equal to the diameter of recess 64 and terminating at a point in alignment with the face of plate 62. By this construction a shoulder 66 is formed between said recess 65 and plate 63, the inner face of said shoulder being of arcuate shape. The depth of recess 65 slightly exceeds the spacing of the adjacent faces of plug 56 and plate 53 of chill 51. A projection 67 of plate 61 is provided at the side thereof opposite plates 62 and 63, and recess 65 is extended into said projection. Recess 65 is adapted to receive member 68 which is provided with an arcuate end 69. This arcuate end 69 engages shoulder 66 and is operatively positioned thereby in a manner whereby said arcuate end 69 is concentric with arcuate recess 64. Member 68 has integrally formed therewith a tapered member 70, of circular cross section, which projects therefrom in the direction of the length thereof. On the end of this member 70 is provided a projecting tapered pin 71, all for purposes to be hereinafter set forth.

In the casting of the heel member of the last, the core 48 is operatively and precisely positioned in the portion of the impression formed in the drag by means of arbor 47 and frame 44. This heel forming core has a recess or pocket 75 formed therein which opens in the direction of chill 61. Member 68 is then inserted in recess 65 of chill 61 with its arcuate end 69 bearing on shoulder 66 of said chill, in which position the tapering members 70 and 71 carried thereby extend centrally into the pocket 75 of said core, with the portion 71 of said member 68 preferably bearing on the bottom end of sand core pocket 75. Member 68 is of a length to project outwardly of the flask members through registering recess 72 formed therein. The cope is then mounted on the drag in registering relation thereto, and the metal is poured into the mold impression. When the metal has set, the member 68 is pulled outwardly through chill recess 65, at least into spaced relation to the recess 28 and pocket 35 formed in the cast member, to prevent the gripping thereof by the cast metal as it shrinks in cooling. The metal entering recess 64 of the chill forms knuckles 27, and the member 68 outlines the shape of the recess 28 of the last between said knuckles, and also the bore of the pocket 32 formed by the metal which enters pocket 75 of the core 48. The tapered pin 71 of member 68 forms an opening in the inner end of pocket 32 of the last part and also serves to prevent the formation of air holes in said pocket member 32. When cast, the heel part of the last is thus complete, except for the finishing of the surfaces other than the joint faces thereof, and for the drilling of the holes 29 which receive the last pivot pin 31.

It will thus be seen that, by the use of this apparatus, the parts of a shoe last may be cast with the knuckles and joint-forming recesses and portions thereof formed integrally and by the same casting operation. Furthermore, the joint faces, including the faces of these joint-forming portions, are cast against the chills and are therefore cast with finished surfaces which may also be somewhat hardened. The finishing of the surfaces in the casting operation assures uniformity and proper fitting of the joint portions and also provides a starting point from which the operation of finishing the remainder of the last parts by machine may be carried on, thus simplifying the problem involved in providing work holders for the machine finishing operation and assuring uniformity of outline of each last part. Another advantage obtained by the use of this apparatus is that one set of chills suffices for the casting of the last members of all sizes and shapes of lasts desired, the only requirement being that the mold impressions be properly formed with relation to the chills to provide the proper positioning of the join parts on the joint face of the member to be cast.

The invention having been set forth, what is claimed as new and useful is:—

1. In a casting apparatus for casting a hollow metal member, a flask having a mold impression formed therein, a core mounted in said impression, and a metal member carried by said flask to form one face of said impression, the face-forming portion of said metal member having a recess formed therein, and a pair of cylindrical members fixedly mounted in said recess in spaced relation to provide the article to be cast with a recessed joint face and a projecting joint knuckle formed in said recess between said cylindrical members.

2. In a casting apparatus for casting a hollow

metal member, a flask having a mold impression formed therein, a core mounted in said impression, a chill comprising two parts having a parting plane and mounted in said flask to form one face of said impression, said chill having a recess formed in said face whose axis is substantially perpendicular to the parting plane of the chill, and a projection carried by said chill in axial alignment with said recess, said chill providing the article to be cast with a joint face including a projecting joint knuckle and a joint recess in axial alignment.

3. In a casting apparatus for casting a metal article, a flask having an impression of the article to be cast formed therein, and a chill comprising two parts having a parting plane and mounted in said flask to form a portion of the outline of said impression, each part of said chill having a recess formed therein and open to said impression whose axis is perpendicular to the parting plane of the chill, and a projection carried by each chill part and extending into said impression in axial alignment with said recess, the recesses of said chill parts registering whereby, said chill provides the joint face of the article to be cast with a joint knuckle and a pair of spaced joint recesses on opposite sides of said knuckles and in axial alignment therewith.

4. In an apparatus for casting a metal article, a two-part flask having an impression of the article to be cast formed therein, and a two-part chill having a parting plane and mounted in said flask to form a portion of the outline of said impression, said chill having a recess whose axis is perpendicular to the parting plane of said chill formed therein and open to said impression, a pair of spaced projections in axial alignment with and on opposite sides of said recess, one of said projections carrying a pin extending toward the other projection to mount a preformed sleeve, said chill providing the joint face of the article to be cast with axially aligned joint recesses and an intermediate joint knuckle having said sleeve imbedded therein.

5. In an apparatus for casting a metal article, a two-part flask having a casting impression formed therein, and a two-part chill having a parting plane and mounted in said flask to form a portion of the outline of said impression, a projection on each chill part and extending into said impression, said projections being spaced, means carried by one of said projections for supporting a preformed tube perpendicularly of said parting plane and in axial alignment with said projections, said chill providing the joint face of the article to be cast with spaced joint recesses and an intermediate joint knuckle all in axial alignment and having the tube imbedded in the knuckle and open throughout its length and removable from said tube supporting means upon separation of the chill parts.

6. In an apparatus for casting a metal article with a projecting knuckle having an open-ended preformed member extending therethrough, a two-part flask having a casting impression formed therein, and a two-part chill having a parting plane, one chill part being mounted in each flask part, said chill parts cooperating to form a face of said impression, said chill parts having axially aligned registering recesses formed in said face and each recess opening to the parting face of said chill to provide an impression of said knuckle, and means carried by said chill for supporting said preformed member coaxially of said knuckle forming impression, whereby metal

flows around said pre-formed member in the casting operation to form said knuckle, and said knuckle with its open ended imbedded member is removable upon separation of the chill parts.

5 7. In an apparatus for casting a metal article, a flask having an impression of said article formed therein, a chill mounted in said flask to form a face of said impression, said chill having a recess formed therein, means carried by said chill for supporting a preformed member in said recess with at least one end thereof bearing on one side of said recess and extending adjacent the opposite side of said recess, said chill having a guide opening extending angularly of said preformed member, and a member mounted in said guide opening to project into said chill recess, whereby said article to be cast is provided with a projection having a preformed member extending therethrough and with a recess extending angularly to said preformed member.

10 8. A chill for use in casting a section of an articulated shoe last and adapted to be mounted in a casting flask to form the joint surface face of the shoe last section impression of said flask, said chill comprising two parts having a parting plane, the joint surface forming face of each chill part having a recess formed therein whose axis is perpendicular to the parting plane of the chill, and a projection carried by each chill part at said joint surface forming face and in axial alignment with said recess, the recesses of said chill parts registering whereby the joint face cast against said chill is provided with space joint recesses and an intermediate joint 15 knuckle in axial alignment.

15 9. A chill for use in casting a section of an articulated shoe last and adapted to be mounted in a casting flask to form the joint surface face of the shoe last section impression of said flask, 20 said chill comprising two parts having a parting plane, the joint surface forming face of each chill part having a recess formed therein whose axis is perpendicular to the parting plane of the chill, a projection carried by each chill part at 25 said joint surface and spaced from said parting plane, said projection being axially aligned with said recess, one of said projections carrying a

pin extending toward the other projection to mount a pre-formed sleeve, said chill providing the joint face of the article to be cast with axially aligned joint recesses and an intermediate joint knuckle having said sleeve imbedded therein. 5

10 10. A chill for use in casting a section of an articulated shoe last and adapted to be mounted in a casting flask to form the joint surface face of the shoe last section impression of said flask, 10 said chill comprising two parts having a parting plane, the joint surface forming face of each chill part having a recess formed therein whose axis is perpendicular to the parting plane of the chill, a projection carried by each chill part at said joint surface and spaced from said parting plane, 15 said projection being axially aligned with said recess, and means carried by one of said projections for supporting a pre-formed tube in axial alignment with said projections and recess, said 20 chill providing the joint face of the article to be cast with axially aligned joint recesses and an intermediate joint knuckle having said sleeve imbedded therein.

25 11. A chill for use in casting a section of an articulated shoe last and adapted to be mounted in a casting flask to form the joint surface face of the shoe last section impression of said flask, 30 said chill comprising two parts having a parting plane, the joint surface forming face of each chill part having a recess formed therein whose axis is perpendicular to the parting plane of the chill, and a projection carried by each chill part at 35 said joint surface forming face and in axial alignment with said recess, said chill parts having registering recesses formed in the parting faces thereof and opening into said first named recess, and a pin disposed in said registering recesses to project into said first named recess, the first named recesses of said chill parts registering whereby the joint face cast against said chill is provided with space joint recesses and an intermediate joint knuckle in axial alignment, 40 said knuckle having an opening formed therein extending angularly of the axis of said knuckle. 45
